(57) **CLAIM**

We claim the ornamental design for a sconce, as shown and described.

DESCRIPTION

FIG. 1 is a perspective view of a sconce of the present invention.

FIG. 2 is a front elevation view of the sconce of FIG. 1.

FIG. 3 is a rear elevation view of the sconce of FIG. 1.

FIG. 4 is a left side elevation view of the sconce of FIG. 1.

FIG. 5 is a right side elevation view of the sconce of FIG. 1.

FIG. 6 is an enlarged top plan view of the sconce of FIG. 1; and,

FIG. 7 is an enlarged bottom plan view of the sconce of FIG. 1.

The broken lines illustrate portions of the sconce that form no part of the claimed design.
